UNITED STATES PATENT OFFICE.

JULIUS SCHIRRA, OF CLEVELAND HEIGHTS, OHIO.

DESIGN FOR A FAN CASING.

Application filed January 23, 1926. Serial No. 16,239. Term of patent 3½ years.

To all whom it may concern:

Be it known that I, JULIUS SCHIRRA, a citizen of the United States, residing at Cleveland Heights, in the county of Cuyahoga and State of Ohio, have invented a new, original, and ornamental Design for Fan Casings, of which the following is a specification, reference being had to the accompanying drawing, forming part hereof, wherein the figure is a perspective view of a fan casing exhibiting my new design.

I claim:—

The ornamental design for a fan casing as shown.

JULIUS SCHIRRA.
